UNITED STATES PATENT OFFICE.

GAETANO LIPARI, OF SAN JOSE, CALIFORNIA.

PROPELLER.

Application filed November 30, 1925. Serial No. 72,256.

It is the object of my invention to provide a propeller with a higher efficiency than the usual screw propellers, so that higher speed may be obtained through its use with substantially the same consumption of fuel and the same driving power, and one that will be exceptionally strong and durable.

In the drawing:—

Figure 1 is a front elevation of my improved propeller.

Figure 2 is a view of the same tilted forwardly and downwardly.

Figure 3 is a plan view of the propeller.

Figure 4 is a sectional view of the propeller on line 4—4 of Figure 1.

Figure 5 is a sectional view of the propeller on line 5—5 of Figure 1.

Figure 6 is a sectional view of one of the propeller blades on line 6—6 of Figure 1.

Figure 7 is a front elevation of another form of my invention.

Figure 8 is a plan view of the same.

Referring more particularly to the drawing I show at 1 a propeller hub adapted to engage a driving shaft along its axis of rotation 2 and provided with oppositely directed and symmetrically arranged blades 3—3.

The bases of the two blades 3—3 merge into one integral whole, the base of one blade curving around the central hub portion 1 and merging with the base portion of the other blade. This formation is clearly shown in Figure 3 where the face 4 of one blade is joined to the corresponding oppositely directed face of the other blade by continuing around and over the hub 1 in a torsional curved surface 5, the other two faces of the blades being joined in a similar manner.

The nature of the curved surfaces 5—5 is of vital importance in this invention, these curved surfaces very closely approaching a cylindrical form. In fact a line drawn from the point 6 on one end of the hub 1 and lying in a plane bisecting the blades and the axis of the hub longitudinally, and drawn over the lowest portions of the surface to point 7 diametrically opposite on the opposite end of the hub as indicated at 8, would

lie almost entirely in the wall of a cylinder having a diameter the same as the hub 1.

One of the results obtained by curving the surfaces 5—5 in this manner is that it brings the heels 9 of the blades close to the hub, the line passing through and bisecting either pair of opposing heels 9—9 as at 10 being at substantially an angle of sixty degrees to the plane bisecting the hub axis and blades longitudinally.

In order to secure the desired curvature of the hub 1 and secure the desired connecting surfaces between the two blades, it is desirable that each blade be turned at an angle of substantially eighty degrees from a plane 65 bisecting the hub axis and blades longitudinally as indicated at 11.

When a propeller of this formation is in use it offers a negligible resistance to the air at the hub, the resisting surface being 70 limited to the diameter of the hub itself. Theoretically it might be said that the air stream at this point as it flows past hub 1, the two blades being enabled to exert their full power upon the air without the disturbing influence of a churning body of air around the hub 1.

In Figures 7 and 8 I show another form of propeller in which the blades are continuous around the hub at substantially the same 80 angle as above set forth, but instead of having the length of the hub equal to the width of the blade as in the embodiment above described, the hub is lengthened along its axis 12 and the blades 13 are connected through 85 a smaller pair of blades 14 extending at right angles to them along the hub. This form is efficient in propelling boats while the propeller hereinbefore described is for use on aeroplanes. In this embodiment one edge 90 of the large blades is curved as at 15 while their opposite edges 16 are twisted midway their length to form the small blades 14.

I claim:—

1. A propeller comprising a hub portion, and oppositely directed symmetrically formed blades formed thereon, said blades being angularly and oppositely directed with respect to a vertical plane bisecting them longitudinally, either surface of one 100

blade being continuous with the oppositely directed surface of the other blade, the lowest portion of the connecting surface passing around the hub in a substantially cylindrical form.

2. A propeller comprising a hub portion, and oppositely directed symmetrically formed blades formed integrally thereon,

said blades being angularly and oppositely directed with respect to a vertical plane bisecting them longitudinally, the bases of the two blades merging into one integral whole, either surface of one blade being continuous with the oppositely directed surface of the other blade.

GAETANO LIPARI.
